UNITED STATES PATENT OFFICE.

ARTHUR BELLINGHAM, OF WOODBRIDGE, ENGLAND.

ANCHOR.

Application filed July 9, 1924. Serial No. 724,956.

To all whom it may concern:

Be it known that I, ARTHUR BELLINGHAM, a subject of the King of Great Britain; residing at The Moorings, Cumberland Street, 5 Woodbridge, in the county of Suffolk, England, have invented certain new and useful Improvements in or Relating to Anchors, of which the following is a specification.

10 This invention has reference to anchors of the kind wherein the stock is disposed, when the anchor is in use, in a plane at right angles to that of the flukes and arms and is secured to the shank by a bolt extending transversely in relation to the stock and the shank. In known constructions of anchors of this kind the stock is in two parts and so pivotally mounted on the shank as to be capable of being moved into planes approximately parallel with that of the shank through the medium of chains or their equivalents whereby the anchor is connected with the boat or other vessel, the stock being thus constructed in order to facilitate 20 the housing of the anchor in a hawse pipe, the said parts of the stock being caused to be actuated upon the same being moved into engagement with the inlet end of the hawse pipe through the medium of the said chains or their equivalents while the parts are caused to be moved in an opposite direction and to be disposed in a position at right angles to the shank when the anchor is clear of the hawse pipe by the connection of the 30 anchor with the said chains or their equivalents.

According to this invention the stock is in one piece and capable of being arranged in a plane parallel or approximately so with that of the shank when the anchor is not in use to enable the anchor under these circumstances to be disposed in an approximately flat condition in the bottom or other part of a boat or other vessel and thereby 40 obviate the inconveniences and accidents due to either the stock or flukes and shank projecting upwardly from the said bottom or other part of the boat or other vessel, very often being the cause of persons being thrown over and sustaining serious injuries, the one piece stock being capable of movement to a position at right angles to the said shank such movement being effected when the anchor is brought into use by the chain 50 or its equivalent which serves to secure it to

the said boat or other vessel and is secured at one end to or near one end of the stock and engages with the shank or a fitting thereon. For the purposes of this invention the stock may be connected to the shank by 60 a hinge, pivot or the equivalent thereof and to the outer end or a part adjacent thereto of the portion of the stock movable away from the shank when the anchor is being collapsed or folded out of use is connected 65 one end of the chain or its equivalent whereby the anchor is attached to the boat, the chain or its equivalent being connected at one end to the end of the stock and passed through rings or equivalent fittings provided at an intermediate point in the length of the shank and at the end of the shank or the centre of the stock and adjustably attached at the other end to the boat.

In order that the said invention may be 70 clearly understood and readily carried into effect the same will now be fully described by way of example with reference to the accompanying drawings, in which:—

Figures 1, 2 and 3 are respectively a front 80 elevation, a side elevation and a plan view of the anchor as it appears with the stock in position when the anchor is in use, the chain being omitted in Figures 2 and 3 to render clear the other parts of the anchor.

Figure 4 is a side elevation of the anchor in a collapsed or folded condition out of use.

The stock *a* is mounted on a pivot pin *b* removably fitted in one end of a channel shaped or equivalent member *c* provided on 90 the upper end of the shank *d*, the opposite end of the said member serving as an abutment for the stock *a* when held in the operative position shown in Figures 1, 2 and 3. On the lower end of the shank *d* are arranged the flukes *e* and arms *f* thereof. The shank *d* between the member *c* and the fluke arms *f* is provided with a ring *g* being loosely connected thereto by an apertured projection *h* on the shank *d*. The chain *j* by which the anchor is connected to the boat has the anchor end thereof connected to a shackle *k* pivotally attached to an extension or lug *l* provided on or near that end of the stock which is moved away from the ring *g* on the shank *d* when the anchor is collapsed as shown in Figure 4, the chain extending from the shackle *k* through the ring *g* and a guide ring *m*, the latter being loosely connected to a projecting plate *n* attached to 100 105 110

the upper end of the shank *d*. Thus arranged the chain *j* serves to maintain the stock *a* in its operative position in a plane at right angles to that of the fluke arms *f* when the anchor is in use and holding the boat against drifting, the chain having freedom of movement relatively to the rings *j* and *m* for transmitting the pull due to the boat. When not in use and arranged within the boat the chain is slack and permits the stock to be moved about the pivot pin *b* to a position approximately parallel with the shank *d* as shewn in Figure 4, thus enabling the anchor as a whole to be disposed flat in the boat without any upstanding parts liable to obstruct persons walking thereover.

It will be understood that various modifications may be made in the construction of the parts for so connecting the stock to the shank as to enable it to be moved relatively thereto, for example the stock may be pivotally mounted on the end of the shank to one side thereof and a projecting pin or block provided to serve as the abutment for the stock when in the operative position, or the chain may be attached to the stock and guided by rings secured in posi-

tion by bolts or devices clamped to their respective parts.

What I claim and desire to secure by Letters Patent of the United States is:—

1. An anchor for boats, comprising a shank, flukes thereon, a stock which is attached to the shank and movable to a position approximately parallel thereto, and a chain connected at one end to the stock near one end thereof and arranged with an intermediate part in engagement with the shank at a point between the stock and the flukes and the other end being capable of attachment to a boat.

2. An anchor for boats, comprising a shank, flukes on one end thereof, a stock in one piece and pivotally attached to one side of the shank at the opposite end to that provided with the flukes an abutment on the shank with which the stock engages when the anchor is in use, a fitting provided on the stock on the opposite side of the shank to the pivotal attachment, an intermediate fitting on the shank, an end fitting on the shank and a chain connected to the fitting on the stock and arranged in engagement with the fittings on the shank.

ARTHUR BELLINGHAM.
